GAS-FILLED DISCHARGE TUBE

Carl J. R. H. von Wedel, Newark, N. J., assignor
to Electrons, Inc., a corporation of Delaware

Application January 20, 1931, Serial No. 509,902

11 Claims. (Cl. 250—27.5)

This invention relates to gas filled discharge tubes having auxiliary electrodes for controlling the operation of the tube

An object of the invention is to provide, in a gas filled tube, suitable control electrodes or grids which will insure more dependable and accurate regulation of the output of the tube, and such that the desired operating characteristics will be maintained during the life of the tube.

More particularly the construction is designed to overcome the undesired effect of grid emission, which is caused by a number of reasons herein-after set forth.

A further object is to provide an effective control for higher operating plate voltages without increasing the discharge resistance in an undesired way which would increase the losses and cause heating of the tube and electrodes.

I accomplish the foregoing objects by the use of a grid of suitable material which does not become emissive and having such configuration as to give suitable control of the electron stream and prevent secondary emission due to ionic bombardment.

Referring to the accompanying drawing,

Fig. 1 shows in perspective a suitable form of grid embodying the principles of the invention;

Fig. 2 is a cross-section through the center of the grid shown in Fig. 1;

Fig. 3 is a comparison of the effect of ionic bombardment tending to cause grid emission between different forms of grids;

Fig. 4 shows a tube embodying the invention, and

Fig. 5 is a modification of the invention.

With regard to the general behaviour of grid controlled gaseous discharge tubes of relatively low internal resistance, only the starting point of general ionization of the gas in the tube can be controlled, and the grid has no further control after the main discharge starts until the plate current supply is discontinued and the discharge extinguished, or until the plate supply passes through zero in the case of alternating current supplied to the plate circuit of the tube. The main discharge in such a tube will start, however, at a point where the product of electronic speed (or voltage acceleration of the electrons on account of the tube field between the discharge electrodes) and the current, or their number per unit of time, arrives at a certain value dependent on the gas used and its pressure in the tube.

The starting point furthermore depends on the type of energy absorbed by the atoms of the gas

present and how these atoms respond in their different stages of excitement with regard to absorbing and reradiating the received energy obtained from the electronic current. Thus as to how and when the main ionization of the gas is introduced is also a question of the kind of work done by the electronic current in the tube. High speed electrons of smaller number will introduce the general ionization in a different manner from low speed electrons of larger current, which means the ionizable atmosphere present will, according to the kind of work done, respond similarly with different atoms of said atmosphere if impurities are present, or may respond with different stages of excitement of similar atoms. In one case large amounts of energy can be absorbed without causing suitable reradiation for excitation of nearby atoms and in the other case the absorbed energy may readily be reradiated and communicated to nearby atoms. In the first case more work must be done or higher losses occur in the tube.

In grid controlled gaseous discharge tubes, particularly those operating on alternating current, the negative potential of the grid in case of ascending plate voltage first acts to deflect the electrons emitted by the incandescent cathode, that is, it will retard these electrons and shield the plate field. When the voltage is rising on the plate, however, occasionally some higher speed electrons will escape and as soon as they pass the grid they are accelerated by the plate field. It may also be said that a positive field is only a less negative field and that the electrons escape towards it being repelled by the more negatively charged space. This plate field, being of the order of some hundred volts, will accelerate these electrons far above the ionization potential of the gas, but as pointed out above, it may not induce the main discharge; its energy will be absorbed or reradiated and there may not be sufficient energy available to keep ionization going on until the atoms near the plate also become ionized. However, if a larger number of electrons escape, even if no general ionization occurs, ions are created at a certain distance from the grid and these are attracted by the grid and start to move toward it.

Here is the point where trouble with the grid will start. As a matter of fact we wish to obtain control of the number of electrons passing the grid and coming from the incandescent cathode and we wish to do this with the static field of the grid in such a way that we control their number safely up to the point where the num-

ber of these electrons emitted by the cathode do the necessary work to induce general ionization. This is the only way to keep the control conditions constant, so that we may be assured 5 that a given plate voltage will start the main discharge if the grid has a certain negative voltage with respect to the cathode. We must therefore avoid disturbances introduced by such first created positive ions between grid and plate, be- 10 cause we have no control over their action.

These positive ions moving toward the grid acquire from the field in the tube different velocities because they are created at different distances somewhere in the space between grid and plate, either directly by the impact of electrons 15 or indirectly by first taking up reradiated energy from other excited atoms. In flying towards the grid the ions may become neutralized there if their speed is very low, and since they are not 20 numerous, they will cause only negligible grid currents to flow. With ions having higher speeds, however, and the grid material being hot or made from substances which will readily emit electrons, they will start to cutout secondary elec- 25 trons, one or more at each impact, and these are accelerated under the plate field and in- 30 crease or cause general ionization which is now not under control. This is particularly likely to happen if the ions strike the grid at a 45° 35 angle or thereabout, because the greatest number of secondary electrons are then cut out.

Furthermore if the grid wires are round and very thin, some positive ions start to travel around them in a planetary orbit until they finally fall on the wires and neutralize their charge. This seems to be one of the most undesired 35 actions causing considerable irregularity of the grid control because these ions, with large iner- 40 tia and slow speed compared to the electrons, by doing so will neutralize the grid field for a large number of electrons coming from the cath- 45 ode and a large amount of them will pass the grid causing general ionization of the tube at an undesired time, and out of control of the grid.

Referring to Figs. 1 and 2, there is shown a 50 grid with a plane portion 1 having openings defined by vanes or ribbons 2 which are perpendicular to the plane portion. The grid is adapted to be mounted so that its vanes are parallel to the main discharge path between the cathode and plate electrodes of the tube. Since the vanes present only their edges to the discharge path, those ions and electrons which strike the grid fall upon a surface which is substantially per- 55 pendicular to their path and are neutralized by the grid, thus causing substantially no secondary emission. The electron stream tending to pass through the relatively large slots 3 is controlled efficiently by the static field set up by the relatively large side surfaces of the vanes. A con- 60 venient way of making the grid of Figs. 1 and 2 is to cut slots in a metal sheet so as to form parallel metal strips, and then twist these strips 90° about their axes so that the edges of the strips are exposed in the direction of the discharge path.

Fig. 3 illustrates how a grid composed of round wires 4 will cause secondary emission of elec- 70 trons created by ions falling on a multitude of surfaces at angles to the discharge path, as compared with a grid composed of vanes presenting only small surfaces which are perpendicular to the ionic stream. Thus, when ions strike the surface of the grid at angles other than the perpendicular, the impact of the ions may cause elec- 75

trons to be thrown off from the grid surfaces, causing the grid to become emissive and inter- 80 fering with the proper control of the tube. Also, the positive ions created before the main dis- 85 charge starts are prevented from traveling in orbits around the grid wires by the extended 90 surface of the flat vanes 2.

The grid should be made of material which 95 will not readily emit electrons under bombard- 100 ment, and should have good thermal conductivity so that it will remain relatively cool. It further should have a low discharge resistance in the direction of the discharge path. Also, if the grid is not sufficiently heat conductive, certain 105 parts of its surface will heat up because, even though the amount of heat in the discharge path 110 may not be great due to the low density of the gas, its temperature is very high, and the heating of parts of the grid facilitates the disturbing 115 secondary emission. 20

It is not essential, however, that the grid be 120 a good conductor of electricity since only a very 125 small current carrying capacity is necessary to establish its operating potential. It is not necessary, therefore, that the grid be made of metal, 130 particularly in the case of high voltage tubes, and 135 materials which have less electrical conductivity, and which do not readily become emitters, may be used. Substances such as carbon or graph- 140 itized carbon mixed with substances such as 145 beryllium oxide, aluminum oxide, zirconium oxide or uranium oxide. A carbon grid according 150 to the invention may be prepared by winding a 155 linen or cotton strip on a metal support so that 160 it forms a grid structure similar to Fig. 1 with 165 parallel ribbons exposing their sides to each other 170 and their edges in the direction of the discharge 175 path. This structure can first be parchmentized 180 and dipped in a solution of a colloid or fine mix- 185 ture of graphite with zirconium oxide and ura- 190 nium oxide or aluminum oxide. It is then placed 195 in an oven and carbonized in a similar way as de- 200 veloped by the art in making carbon filaments for 205 lamps. The whole grid structure can thereafter 210 be heated in a hydrocarbon or cyanogen atmos- 215 phere to carbonize its whole surface as far as it is 220 exposed to bombardment, and contains metal 225 parts for support. 45

All highly emissive incandescent electrodes 230 sputter or vaporize to a certain extent during 235 the process of manufacture and when the tube 240 is in service, particularly in the case of cathodes 245 coated with oxides of the alkaline earth metals. The coating is sputtered onto or condenses on the 250 grid surface and tends to make the same more 255 emissive. Therefore, it has been found desir- 260 able in practice to make the grid of a material 265 which will neutralize the emissivity of deposits 270 of vaporized cathode material. In case the grid 275 is metallic, such metals should be used the hy- 280 droxides of which are definitely acid, such as 285 tungsten or tantalum or at least more acid than 290 the hydroxide of molybdenum. Such metals 295 have the property of combining with the alkaline 300 earth metals on their surface and forming for 305 instance, tungstates (because always some oxy- 310 gen is freed in the tube) which are not emissive 315 or are poor emitters. 65

Fig. 4 shows a discharge tube having an envelop 6 with reentrant end portions 7 and 8 sup- 70 porting the electrodes, the tube being filled with 75 gas, preferably an inert gas such as argon, al- 80 though other ionizable atmosphere may be em- 85 ployed, such as mercury vapor, or a mixture of 90 mercury vapor and inert gas. The cathode as- 95

sembly 9 comprises an open ended can 10 enclosing a plurality of emissive filaments 11, preferably of the oxide coated type. The resultant compound from a mixture of an alkaline earth metal, such as barium, calcium or strontium oxide and the oxide of a metal the oxy-acid of which is less acid than titanic acid, such as aluminum oxide or zirconium oxide, comprises a desirable coating. The space directly between the upper open end of the cathode and the anode 14 is surrounded by a grid 12 of a form particularly suitable for high voltage tubes. A circular carbonized metal disk or shield 13 by which the discharge path is deflected to obtain a shielding action to prevent back-arching from the anode 14—in the event it becomes negative—is placed close to the anode 14, approximately within the mean free path of the electrons, with a given gas pressure in the tube, so that any electrons freed from the anode will not strike an arc, but will travel at such short distances only that ionization resulting therefrom is insufficient to introduce the main discharge. The electron stream from the cathode passes out through the slots between the vanes 2 in the cylindrical side portion of the grid. The vanes extend radially, and their edges point in the direction of the electron stream, so that the sides of the vanes do not present angular surfaces to the electron path.

30 The grid is surrounded by a flanged annular shield 15 which extends in close proximity to the wall 6 of the tube, thus providing a good heat radiating surface near the cooler portion of the tube and also intermediate the ends of the tube where the heat radiated to its wall will not affect or tend to break the seal of the envelope. This extending shield also cooperates with the negative charge which is normally present on the tube wall and shields the portion of the tube above 40 the grid from that below and thus prevents any discharge around the grid.

The plate supporting wires 16 are preferably enclosed with protective insulation or shielding means 17 to prevent ionic bombardment of the conductors.

Fig. 5 shows a construction which is adapted for high plate voltages of different value, and in which two grids 21 and 22 are placed in the discharge path in such manner as to reduce the discharge resistance of the tube. In this case the grid 22, which is near the cathode, may be made of metal if desired, and the grid structure 21, which is near the anode 23, should preferably be made of non-emissive carbon and oxide com- 55 pounds, such as mentioned hereinbefore.

The grid structure 21 surrounds the plate 23 and serves to partially shield or neutralize the lines of force from the plate and also serves as a shield for the plate lead-in conductors 16 and 60 their insulating covering 17 from ionic bombardment. The grid, or at least that portion of it behind the plate, is placed within a distance from the plate approximately equal to the mean free path of the electrons. The grid is preferably 65 connected to the plate circuit by means of a current limiting resistance 23 and variable connection 24 to the plate supply transformer 25, and its potential can therefore be made more or less positive with respect to the cathode and control 70 grid 22. In this manner the character of the work done by the electrons which introduce the discharge between the grids may be varied, as heretofore explained, so that the tube can be caused to operate under the most favorable conditions and in accordance with the plate voltage 75

and load applied thereto. Grid 21 may, however, be connected to the control grid 22, if desired.

The tube may be employed in any suitable circuit. As shown, the control grid 22 may be maintained at a negative potential with respect to the cathode, and its potential may be controlled by potentiometer 28 connected to the grid by conductors 27 and 28. The potentiometer is connected across a source of direct current 30 whereby the potential on the grid may be adjusted, the source of direct current being connected to the cathode through the secondary winding 31 of a transformer 33. The primary winding 34 of the transformer is connected, in series with a phase shifting impedance 32, to the plate supply, to 10 impress an out of phase alternating potential on the grid 22 to control the starting point of the tube throughout the entire alternating current cycle.

Any of the foregoing grid structures may have 20 different shapes other than that shown, such as a ribbon wound in the form of a spiral, or parallel ribbons arranged in criss-cross relation, so as to obtain small surfaces exposed in the direction of the discharge and substantially perpendicular 25 thereto, with larger surfaces parallel to the discharge path.

What I claim is:—

1. A grid controlled gaseous discharge tube comprising a thermionic cathode, an anode, and an electrostatic control electrode therebetween, disposed in an ionizable atmosphere of substantially constant density throughout the tube, the control electrode comprising spaced apart strips with relatively thin edges disposed in the discharge path between said anode and cathode with their edges substantially perpendicular to the paths of ions impinging thereon and with their larger lateral surfaces parallel to said paths, said strips being spaced from the anode a distance 40 greater than the mean free path of said gas filling.

2. A grid controlled gaseous discharge tube comprising an envelope, a rare gas atmosphere therein, a thermionic cathode, an anode, an impervious shield disposed between said cathode and anode transverse to the direct path therebetween and extending close to the wall of said envelope, said shield having an opening therein, and a series of thin spaced apart vanes bridging said opening and forming a starting control grid, said vanes presenting only their edges to the ions impinging thereon.

3. A discharge tube comprising an envelope, an ionizable atmosphere therein, an electron emissive cathode, an anode, a shield disposed between said cathode and anode obstructing all straight discharge paths therebetween, a grid surrounding said shield, and means surrounding said grid and cooperating with said shield and grid for electrically shielding that portion of the envelope containing the anode from that portion thereof containing the cathode.

4. A discharge tube as defined by claim 3 in which the first-mentioned shield is spaced from the anode a distance determined by the mean free path of the atmosphere in said tube whereby back-arching is prevented.

5. A grid structure for a gaseous discharge tube comprising a central conductive member, an outer conductive member surrounding the central member but spaced therefrom, both said members being impervious to the passage of electrons and ions therethrough, and a control grid comprising a series of vanes disposed in the space be- 70 75

tween said members and providing therein a series of slots defined by the lateral surfaces of said vanes.

6. A grid controlled gaseous discharge tube comprising an anode, a thermionic cathode, a filling of inert gas adapted for a low voltage gaseous arc discharge between the cathode and anode, and a control electrode the potential of which determines the starting of said discharge, said control electrode comprising spaced apart strips disposed in said discharge path with their thin edges perpendicular thereto and exposing their larger lateral surfaces substantially parallel to a small portion of the length of said path, said strips being located a distance from the anode greater than the mean free path of said gas filling.

7. A grid controlled gaseous discharge tube comprising a substantially cylindrical envelope, an anode and a thermionic cathode disposed therein and aligned on the axis of said envelope, an inert gas filling providing a gaseous arc discharge path between the anode and cathode, and a third electrode disposed therebetween with a plane portion of said electrode perpendicular to said axis and extending close to the envelope wall, said electrode comprising means for controlling the starting of the gaseous arc discharge between the anode and cathode including a series of vanes spaced apart and so disposed relative to the ions created in the tube prior to the starting of said discharge that said ions strike the edges of the vanes perpendicularly or pass the vanes substantially parallel to their lateral surfaces, said vanes being spaced from the anode a distance greater than the mean free path of said gas filling.

8. A grid controlled discharge tube comprising an envelope containing an ionizable atmosphere, an anode and a thermionic cathode spaced apart therein a sufficient distance for an arc discharge through said atmosphere, conductive shielding means comprising members near the anode and cathode respectively, said members being widely spaced from each other compared to the space between the anode and the member near it, both said members restricting the available space for

the passage of said discharge from anode to cathode, a starting control grid disposed within said restricted space, and a lead-in conductor for said grid sealed in the envelope wall at a point remote from all conductive parts of the other electrodes.

9. A grid-controlled gaseous discharge tube comprising an envelope, an ionizable atmosphere therein, a thermionic cathode, an anode, and conductive control means having an electron impervious portion thereof spaced from the anode within the mean free path distance in said atmosphere and a perforate portion thereof spaced from said anode a distance greater than the said mean free path, said impervious portion being disposed in the direct path between said anode and cathode to lengthen substantially the discharge path therebetween.

10. A discharge tube comprising an envelope containing an anode, a thermionic cathode and an ionizable atmosphere adapted in combination to produce a low resistance arc discharge from anode to cathode, a starting control grid, a discharge impervious conductive shield disposed between the anode and grid, and a conductive shield disposed between the grid and cathode and spaced from the first said shield a distance greater than the mean free path of electrons in said atmosphere, the said grid being disposed in the space between the shields.

11. A discharge tube of the type in which a starting control means loses control of the discharge current after it is started, said tube comprising an envelope containing an ionizable atmosphere, an anode and a thermionic cathode disposed therein to provide sufficient space from anode to cathode for an arc discharge therebetween, discharge impervious conductive shields restricting the cross sectional area of said envelope at two or more points between the anode and cathode, said points being spaced apart a distance greater than the mean free path of electrons in said atmosphere, and starting control means disposed between said shields.

CARL J. R. H. VON WEDEL.
